Green O Bush

By Lucy H. Moore.

Attorney.

UNITED STATES PATENT OFFICE.

GREEN O. BUSH, OF LUVERNE, ALABAMA.

REFRIGERATOR.

1,398,769.

Specification of Letters Patent. Patented Nov. 29, 1921.

Application filed April 13, 1920. Serial No. 373,582.

To all whom it may concern:

Be it known that GREEN O. BUSH, a citizen of the United States of America, residing at Luverne, in the county of Crenshaw and State of Alabama, has invented certain new and useful Improvements in Refrigerators, of which the following is a specification.

My invention has reference to improvements in refrigerators of the cooled air type and it is the principal object of the invention to provide a refrigerator for preserving various foodstuffs placed therein in an eatable state and prevent the same from being affected by the presence of other foodstuffs in the refrigerator, as is often the case where foodstuffs are placed indiscriminately in a refrigerator, the odor from one affecting the other to such an extent as to detract from the taste of the same, if not often times spoiling it.

More specifically it is the object of my invention to provide a refrigerator having a plurality of individual or distinct compartments for receiving various foodstuffs to be preserved, each of said compartments having the cooling medium therefor circulating therethrough in a manner which will maintain the same at their lowest temperature.

The foregoing together with additional advantageous arrangements and features of construction of my improved refrigerator will be brought out more in detail in the description to follow, which for a clear understanding of the invention, should be considered in connection with the accompanying drawings forming a part thereof and wherein a convenient and satisfactory embodiment of the invention is shown for the purpose of illustration.

In the drawings:

Figure 1 is a vertical longitudinal section through my improved refrigerator, a portion of the front wall thereof, being fragmentally shown; and

Fig. 2 is a vertical transverse section through the same, and Fig. 3 is a front elevation of my refrigerator showing the individual doors for each compartment.

Having more particular reference to the drawings, in connection with which like characters of reference will designate corresponding parts throughout the several views, the improved refrigerator comprises a hous-

ing indicated by the numeral 1, divided into a plurality of separate air-tight compartments designated by the numerals 2, 3, 4 and 5 respectively, the compartment 3 being provided with a sloping bottom 6 formed with a central drain 7 having the usual cap 8 engaged over its lower end whereby to form an air seal.

It will be noted that the compartments 2 and 3 are arranged in superposed relation, one being separated from the other by means of a rack 9 on which the ice placed in the compartment 2 is supported, drippings from the ice going into the compartment 3 and from the same by way of the drain 7.

The compartments 4 and 5 are also arranged in superposed relation upon either side of the compartments 2 and 3 and are separated from each other by partitions 10. These compartments serve to receive the various foodstuffs to be preserved in the refrigerator.

As means for maintaining the compartments 4 and 5 at temperatures corresponding to the compartments 2 and 3, I tap into the upper end of the compartment 2 through the several side walls thereof, the ends of a plurality of sets of horizontally aligned pipes 11 as clearly shown in the Fig. 1, said pipes extending horizontally through the upper portions of each of the uppermost compartments 4 and 5 to points adjacent the outer side walls of the same, whereat, they are bent at substantially right angles and passed downwardly through the other compartments 4 and 5 to points adjacent the bottoms of the several lowermost compartments 4 and 5, whereupon they are again bent inwardly at substantially right angles and have their free or remaining ends tapped into the lower portion of the compartment 3 through the several side walls of the same.

From the foregoing it will be understood that with ice or other refrigerant in the compartment 2, the air passing therefrom in its cooled state, will be conveyed through the several sets of pipes 11 extending through the compartments 4 and 5, thus bringing the same to the approximate temperature of the compartments 2 and 3, and thereby maintain the foodstuffs therein at proper temperature to insure preservation of the same. Further by reason of the connection of the pipes 11 with the lower por-

tion of the compartment, a complete circuit or path of travel will be afforded the cooled air in the pipes 11 and in consequence, the same will be maintained at a temperature 5 corresponding to that of the compartments 2 and 3.

The front wall of the refrigerator indicated at 12, serves to partially close the forward sides of the compartments in the 10 refrigerator, having suitable individual openings therein adjacent each of the same, which are adapted to be closed by doors of suitable design such as fragmentally shown and designated at 13 in the drawing. Thus, 15 access may be had to these compartments, as may be desired.

Suitable legs 14, may be and preferably are provided the housing 1, serving to support the same at the height desired.

20 The housing 1 and its various doors may, of course, be constructed of any recognized heat-insulating material or if desirable, may be constructed of double walls providing for dead air space therebetween, as is common 25 practice in this art.

Manifestly, the construction shown is capable of considerable modification and such modification as is within the scope of

my claim I consider within the spirit of 30 my invention.

What I claim is:

A refrigerator comprising a housing divided into a plurality of compartments, certain of which communicate with each other, while others are distinct and unrelated, the 35 bottom of the lowermost of said communicating compartments being sloped and formed with a drain, sets of horizontal aligned cooling pipes connected at their free ends to the opposite sides of the upper and 40 lower portions of the communicating compartments and being disposed adjacent the tops and bottoms of the upper and lower of said unrelated compartments, while the intermediate portions of the pipe extend 45 through the unrelated compartments adjacent their outer walls and individual doors in one wall of the housing for each of said compartments.

In testimony whereof I affix my signature 50 in presence of two witnesses.

GREEN O. BUSH.

Witnesses:

J. I. BROOK,
J. T. VAUN.
